UNITED STATES PATENT OFFICE

WILLIAM D. FERRIS, OF STERLING, ILLINOIS, ASSIGNOR TO FRANTZ MANUFACTURING CO., OF STERLING, ILLINOIS, A CORPORATION OF ILLINOIS

SPRING CATCH

Application filed August 18, 1928. Serial No. 300,599.

This invention relates to spring catches of the kind in which a pair of spring jaws are secured to the stationary portion of a cupboard or cabinet, or similar structure, and in which an engaging member is then secured to the door in position to enter between said spring jaws, when the door is closed, thereby to frictionally hold the door in closed position.

10 Generally stated, the object of the invention is to provide said spring jaws in such form that they can be used on cupboards or cabinets in which the ordinary spring jaws could not be employed without considerable trouble and labor, and of such form that the catch is applicable to situations where it would not be practicable, even if possible, to employ a spring catch having the ordinary form of spring jaws.

20 It is also an object to provide certain details and features of construction tending to increase the general efficiency and desirability of a spring catch of this particular character.

25 To the foregoing and other useful ends, the invention consists in matters hereinafter set forth and claimed and shown in the accompanying drawings, in which—

Fig. 1 is either a plan or a side elevation of 30 a spring catch embodying the principles of the invention, showing fragments of the adjacent portions of the cabinet or cupboard.

Fig. 2 is an enlarged section on line 2—2 in Fig. 1.

35 Fig. 3 is a perspective of the spring jaw unit shown in Figs. 1 and 2 of the drawings.

As thus illustrated, the wall 10 of the cabinet or cupboard may be either a vertical or a horizontal wall, depending upon conditions 40 and requirements. The door 20 is preferably hinged to swing about a vertically disposed axis, in any suitable or desired manner.

The spring catch unit shown in Fig. 3 of the drawings comprises the base strip 1 provided with screw holes 2 near each end thereof, whereby screws 3 can be inserted through said strip into the wall 10 to secure the spring jaw unit in operative position. Said unit has a wall 4 disposed at right angles to the strip 1, integral with one edge thereof, and

this wall 4 has two integral jaws 5 extending across the strip 1 as shown. The unit is made from a single blank of springy sheet material, and a stiffening bead 6 extends a distance over the center of the strip 1, and a short distance over the adjacent surface of the wall 4, thus reinforcing the right-angle bend or corner between the walls 10 and 4 of the unit. This bead 6 is formed in any suitable manner, as by pressing the sheet metal to 55 provide the bead in the desired form.

The door 20 is provided with an engaging member 7 formed preferably from a single strip of sheet metal bent into shape to provide a sort of reversely tapered tongue for entrance between the spring jaws 5 previously mentioned. The end of this tongue is more or less pointed, so that it can be pushed between the jaws, when the door 20 is closed, and the taper of the tongue toward the base 65 portions thereof, which portions are secured in place by the screws 8, then provides a frictional grip between the jaws and tongue to 70 frictionally hold the door in closed position.

It will be understood that the door 20 can 75 be provided with a knob or handle (not shown) for forcibly opening and closing the door, to engage and disengage the tongue 7,

in a manner that will be readily understood. It will be seen that with this construction 80 the spring jaw unit has a comparatively narrow footing or base, the base 1 being comparatively narrow, and the jaws 5 being comparatively short. In this way, therefore, said spring unit can be secured in position on cupboards and cabinets in which a longer spring 85 jaw unit, or one having a longer base or footing, could not be used, or could only be used by resort to considerable trouble and labor, as the carpenter or cabinet-maker in applying 90 the catch would, with the ordinary form of spring catch of this type, be put to some extra labor in building out to accommodate for the greater length of jaw unit. With the construction shown and described, however,

95 which is illustrative of the invention, the spring jaw unit is considerably shorter than is ordinarily the case, so that it can be secured in position where a longer unit could not be used, or could not be used without extra labor. 100

The construction is strong, as the bead 6 prevents the wall 4 from being bent backward, by the thrust of the tongue 7 in closing the door. Moreover, the spring jaw unit is easy to install, as the screw holes 2 are outside of the two jaws, thus making it more convenient to fasten the spring unit in place. The base 1 is under the two spring jaws, and does not extend beyond the rear ends of these jaws, but this does not in effect reduce the length and flexibility of the jaws, inasmuch as the lower edges of the jaws are not fastened to or united with the top surfaces of the strip 1, but are only connected to this strip through the medium of the wall 4, which is integral with the rear edge of the said base strip. Thus, while the jaw unit is substantially only about half as long as the ordinary spring jaw unit of this general character, the jaws themselves are no shorter and are practically just as long as those of the ordinary unit. Many cupboards or cabinets are so designed and built that a narrow wooden strip or stop, sometimes only about five-eighths of an inch in width, is all the footing upon which a friction catch spring jaw unit can be applied, except by extra work. However, with the construction shown and described the catch can be applied without extra work or labor, even in cabinets or cupboards where the footing for the spring jaw unit is of minimum width.

Without disclaiming anything and without prejudice to any novelty disclosed, what I claim as my invention is:

35. 1. In a spring catch, a spring jaw unit comprising a pair of spaced spring jaws adapted to receive an engaging member between them, said unit having a base extending under or back of the jaws, toward the free ends of the jaws, with the adjacent edges of the jaws free to move back and forth over the face or outer surface of said base, and means connecting the rear edge of said base to the rear ends of said jaws, forming a connection between the rear ends of said jaws.
40. 2. A structure as specified in claim 1, said means comprising a wall integral with the base and both jaws, the entire unit being formed from a blank of sheet metal.
45. 3. A structure as specified in claim 1, said means comprising a wall integral with the base and both jaws, the entire unit being formed from a blank of sheet metal, said base and wall having a bead forming a brace to reinforce and stiffen the right angle junction between said wall and base, between said jaws.
50. 4. A structure as specified in claim 1, said base having screw holes outside of said jaws, whereby to fasten the base to a stationary portion of the cabinet or cupboard.

Specification signed this 10th day of August, 1928.
